HEMOGLOBINOMETER.

1,083,934.

Specification of Letters Patent.

Patented Jan. 13, 1914.

Application filed December 11, 1911. Serial No. 685,118.

To all whom it may concern:

Be it known that we, EDUARD KÖBNER and PAUL FRITZSCHING, subjects of the German Emperor, residing at Mannheim, in the 5 Grand Duchy of Baden, Germany, have invented certain new and useful Improvements in Hemoglobinometers, of which the following is a specification.

This invention relates to certain new and 10 useful improvements in hemoglobinometers, such as are used for testing the blood, and more particularly for determining the percentage of hemoglobin in the blood.

The invention has for its main object to 15 provide a device of this character of a neat and compact size which will permit of the same being used immediately when the patient is being examined and independently of a dark room, a special source of light, or 20 other special circumstances.

A still further object of our invention is to provide a device of this character embodying the colorimetric system in which the different shades of the color are arranged 25 on a rotatable disk provided with a perforation through each field of color and in which the fields of color may be brought to the filtering or blotting paper carrying the blood sample, the device also having means for 30 conveniently carrying the filtering or blotting paper used. Furthermore, to provide a device of this character embodying an inclosing case which acts to exclude all foreign matter from the filtering or blotting paper and also to exclude light from the varicolored percentage disk.

The invention consists in the novel construction, combination and arrangement of parts which will be hereinafter more fully 35 described and then particularly claimed, and in describing the invention in detail, reference will be had to the accompanying drawing forming a part of this application and wherein like numerals of reference will be 40 employed to indicate like parts throughout the different views of the drawing, in which:—

Figure 1 is a view in front elevation showing 45 the instrument with the paper-carrying section of the inclosing casing removed. Fig. 2 is a similar view of the paper-carrying section of the casing. Fig. 3 is a detached view in elevation of the colorimetric disk. Fig. 4 is a transverse vertical sec- 50 tional view with the two sections of the in-

closing casing of the device separated, and, Fig. 5 is a detail view in top plan of a portion of the disk-carrying section of the casing.

To put our invention into practice, we 60 provide a circular box or casing which comprises two separable members or sections, and which in practice are generally made of card board or similar material, though of course we do not confine ourselves to any 65 specific material. The main member or section of this box or casing comprises a back 10 with a circular wall 11 on its front face slightly less in diameter than the diameter of the back, the other of said members or 70 sections being in the nature of a lid and comprising a cover plate 12 having an annular flange 14 of a diameter to fit neatly over the wall 11, the relative width of the wall 11 and flange 14 being such that when 75 the sections or members are placed together, the free edge of the flange 14 will abut against the back 10 outside of the wall 11, and the free edge of the wall 11 will abut against the inner face of the lid or cover 12. 80 At a point in its periphery, such point being herein designated as being at the top, the wall 11 is provided on its inner edge with a cut-away portion or slot 15, for a purpose as will hereinafter more fully appear. It is desirable, though not essential, that the inner face of the back 10 be provided with a facing 16 which may be of a stiff material to add rigidity to the back, and may be colored darkly so as to present 85 no light surfaces adjacent the color card. This backing, in case the back 10 be of a dark color, may obviously be dispensed with. Where employed, however, it will be cut away at its top edge as shown in Fig. 4 at 90 16', so as not to interfere with the insertion through the slot 15 and in front of the backing, of the filtering or blotting paper carrying the sample of blood, and to be herein-after more fully referred to. 100

Fitted within the main member or section of the box or casing is a face plate 17, the inner face of which rests at its edges against the stop 18 provided within the main section of the box or casing, and which face 105 plate at its upper side has a substantially V-shaped or sector-shaped cut-away portion 19 extending inwardly from the periphery thereof to a point in close proximity to the axis of the plate. This face plate carries 110

centrally thereof a pintle 20, or equivalent device, which rotates in the face plate and carries on its inner end the color disk 21, which disk is of slightly less diameter than the face plate, so as to freely rotate within the wall 11. The said pintle may be of any desired form, such as will fasten the color disk so that it will rotate as the pintle is rotated, such pintle being provided on its outer end with a suitable gripping member 22 herein shown as being in the form of a small ring, since such device when not in use, will lie flat against the face plate 17. The pintle here shown is formed from a single piece of wire doubled upon itself and having its free ends spread apart after being passed through the color card and a small disk 23, the ends of the pintle being fastened to said disk, and the disk being fastened to the color card, so that when the pintle is turned in the face plate, the color card and disk will rotate with the pintle. The disk 23 above referred to also acts as a seat for the lower end of the piece of blotting or filtering paper inserted in the box or casing in back of the color card. The said color card, as stated, is in the form of a disk, and this disk is divided into equally-spaced substantially triangular fields or sectors 24, nine of which are shown, of different shades of the color of blood and indicating by the depth of color the percentage of hemoglobin in the blood, from 20 to 100%, the remaining field of the color card being preferably left blank, so that when the device is not in use, this blank field may be turned opposite to the cut-away portion 19 and all of the colored fields will be concealed behind the face plate so as to exclude the light therefrom. The uncolored field 25, as stated, is left blank, but each of the colored fields are provided with a sight opening 26.

For use in connection with the apparatus, we employ a filtering or blotting paper which will readily absorb the blood, and we have found it convenient to arrange this paper in circular pads, each sheet of the pad being perforated from the periphery to the center so as to provide sections 27 of a shape conforming to the fields of the color card. The pad of paper designated 28 in Fig. 4 is fastened to the lid or cover plate 12 by an eyelet 29 or any other suitable means.

Such being the construction of the device, its manner of use will it is believed, be obvious, but may be briefly stated as follows: When a test of the blood is to be made, the physician or operator detaches one of the sections 27 of the filtering or blotting paper, and after the desired quantity of blood has been absorbed thereby, such section of the paper is inserted in the slot 15, and the operator by turning the pintle 20 brings the different shades of color successively over the filtering or blotting paper until the

matching color is observed through the proper sight opening 26. The figures which stand opposite that shade of color which most nearly corresponds with the color of said sample, give the percentage of hemoglobin in the blood under examination. 70

It is understood of course that an examination of the quantity of hemoglobin by the aid of a scale of colors, such as described, may not give such exact results as may be 75 obtained when a hemometer is used for the purpose, but extensive experiments by us have proven that such exactness diviates but slightly from the results obtained by the use of complicated apparatus designed for 80 the purpose of obtaining the amount of hemoglobin in the blood.

Having, fully described our invention what we claim as new is:

1. In a hemoglobinometer, a box or casing 85 comprising two separable sections, a color disk rotatably-mounted in one of the sections and having a plurality of sectors of different shades, each sector having an opening therethrough, the rim of said section being provided with a receiving slot, the other section of said box constituting a cover. 90

2. In a hemoglobinometer, a box or casing comprising two separable sections, one of which has a circular wall provided with a 95 receiving opening, a disk rotatable in said section and having its outer face divided into fields of different shades, said disk provided with an opening through each field of color, a face plate frictionally fitting 100 within said wall and carrying said color disk, the other section of said box constituting a testing paper-carrier and a cover for the main section of the box.

3. In a hemoglobinometer, a circular box 105 or casing having a slot through the wall to receive a piece of testing paper, and a color disk rotatably-mounted in the box with its outer face divided into fields of different shades and having openings therethrough 110 through which the paper inserted in said slot may be observed.

4. In a hemoglobinometer, a circular box having its wall provided with a slot at one point, and a rotatable color disk mounted within the box, the color disk having its outer face divided into fields of different shades and having openings through the disk within the boundaries of the fields, through which paper inserted through the 120 slot may be observed.

5. In a hemoglobinometer, a circular box provided at a point in its walls with an insertion slot, a color card rotatably-mounted within the box and having its outer face divided into fields of different shades and further provided with openings therethrough within the boundaries of the fields for observance of material inserted through said slot, and a cover member for said box. 130

6. In a hemoglobinometer, a box comprising a card holding member provided with an insertion opening, a color card rotatably-mounted within said member and having its outer face divided into fields of different shades and further having side openings for the observation of material introduced in said box member through said insertion opening and in back of said color card, and 10 a cover member fitting on said card holding member to exclude the light from said color card when the device is not in use.

7. In a hemoglobinometer, a card holding member comprising a back having an annular flange of less diameter than the back, 15 said flange provided with an insertion slot, a color card rotatably-mounted within said

member and having its outer face divided into fields of different shades and further having side openings through which material inserted through said slot may be observed, and a cover member comprising a front plate and a rim, the rim fitting over the flange of the back plate and covering said insertion slot, the said cover constituting 25 a carrier for the material inserted through said slot.

In testimony whereof we affix our signatures in presence of two witnesses.

EDUARD KÖBNER.

PAUL FRITZSCHING.
